UNITED STATES PATENT OFFICE.

JOHN M. CALLOW, OF SALT LAKE CITY, UTAH, ASSIGNOR, BY MESNE ASSIGNMENTS, TO PNEUMATIC PROCESS FLOTATION COMPANY, OF NEW YORK, N. Y., A CORPORATION OF DELAWARE.

METHOD OF AND APPARATUS FOR CONCENTRATING ORES.

1,329,335.

Specification of Letters Patent. Patented Jan. 27, 1920.

Application filed April 1, 1914. Serial No. 828,805.

To all whom it may concern:

Be it known that I, JOHN M. CALLOW, a subject of the King of Great Britain, residing at Salt Lake City, in the county of Salt Lake and State of Utah, have invented certain new and useful Improvements in Methods of and Apparatus for Concentrating Ores, of which the following is a specification.

10. My invention relates to a method of and apparatus for concentrating metallic ores by separating the metallic particles from the barren or rocky constituents thereof and the invention consists of the method and the 15 parts and the constructions, arrangements and combinations of parts which I will hereinafter fully describe and claim.

In the accompanying drawing forming a part of this specification and in which 20 similar letters of reference indicate like parts in the several views:—

Figure 1 is a longitudinal, vertical sectional view of an ore concentrating apparatus embodying the salient features of my 25 invention.

Fig. 2 is a top plan view of the same, showing certain of the parts omitted.

Fig. 3 is a rear elevation of Fig. 1.

Fig. 4 is a front elevation.

30. Figs. 5, 6 and 7 are modifications of the porous medium hereinafter described.

In said drawings, the tank, A, may have any suitable dimensions, as to its length, height and width, these depending upon its 35 capacity, and said tank may be formed of any suitable material. I consider angle-iron and sheet iron as well adapted for the construction of the tank and accordingly, I have shown this material in the drawings.

40. The tank has parallel sides, a, and, therefore, it is of uniform width from front to rear, and at equal distances along each of these sides are arranged vertical guides, b, to which are fitted the vertically-disposed 45 plates, c, which constitute baffles and which may be raised and lowered to increase or decrease the space below their lower edges.

The arrangement described is such that the baffles combined with the sides of the 50 tank form a series of chambers or compartments in the tank which communicate with each other through the space formed under the lower edges of the baffles.

The tank has a bottom, d, which slopes

downwardly from the rear end to the front 55 and this bottom has bolted or otherwise connected to it suitable sockets or plates, e, adapted to receive appropriate legs, f, upon which the tank may be supported.

The tank may also be of sectional character with the upper section, A', having fitted to it the aforesaid baffles and being open at the bottom; the lower section, A'', is rigid with the bottom proper which is suitably spaced below the baffles and to which bottom the leg-sockets, e, are bolted or otherwise secured, as shown in Fig. 1, the two sections of the shell being secured together in any suitable manner.

At one end, say the rear, the tank is provided with an opening or passage, g, into which the pulp is received from any suitable source. This pulp may be of the character usually employed in the buoyant processes, namely, a mixture of mineral-bearing pulp, 75 and a frothable agent having a preferential affinity for metalliferous matter. The pulp upon its being received into the passage, g, is delivered into a pocket or chamber, h, formed at the rear end of the cell, 80 and communicating upwardly through the bottom of the first compartment, or chamber of said tank, thus permitting the pulp to successively enter the compartments of the tank from below and under the several 85 baffles, the pulp gradually filling the compartments or chambers of the tank until the proper level has been reached.

On the inside of the bottom of the cell and which bottom is arranged at an incline, 90 as before stated, are riveted or otherwise secured suitable angle-iron or other upright members, i, which, with the side walls of the bottom section, A'', of the cell constitute independent cells, k, each of which underlies one of the pulp-containing compartments or chambers of the tank. The several cells, k, are designed as receivers for air, 95 gas or vapor, under pressure, and in order that the same may be delivered into the 100 separate compartments of the tank overlying the air cells and may be admitted into the pulp in such manner as to form a satisfactory froth, foam or suds, I prefer that the top of each air cell shall be substantially a 105 porous medium, l, through which the air, gas, or vapor, under pressure, in the cell below, will escape in innumerable fine streams,

or jets, this being for the purpose of producing a froth composed of bubbles of air, gas or vapor having an envelop or covering of oily matter, to which the mineral particles 5 in the pulp have an affinity and will attach.

The porous medium may be of any suitable character and construction; porous brick, as shown in Fig. 1, or a layer of fine sand 10, Fig. 5, between two restraining layers of 10 screen cloth, 11 or layers 12 of fibrous material laid one above the other as in Fig. 6, such as cocoa matting, or porous wood, as bass wood, or one or more layers, 13, Fig. 7, of any suitable fibrous material, as can- 15 vas or filtering cloth, capable of subdivid- ing the air, gas, or vapor into more or less irregular jets of infinite number and fine- ness may be used and are within the scope of my invention. The character of the porous material employed is unimportant except that it shall have the function of permitting air introduced into the cell to be discharged through the pores of the material, and into the body of pulp in the cham- 20 ber above, with the result that immediately upon the introduction of the air into the pulp a froth, foam or suds begins to form and to rise and collect on the surface of the pulp contents, which froth, foam or suds 25 gradually increases in volume and density as the action proceeds.

It will be understood that this frothing or foaming action occurs in each of the chambers of which the tank is composed and 30 that there may be as many of these chambers as desired, this depending upon the capacity of the apparatus.

It is also apparent that the volume of air, gas, or vapor admitted into each of the 35 compartments may be so regulated as to provide just that amount which is required for the capacity or size of the chamber formed in the compartment immediately above a particular air-cell, which may be desirable 40 because as before stated, the compartments of the tank increase in size from the inlet to the discharge end of the tank and conse- 45 quently the amount of air, gas, or vapor re- quired for the larger chambers will be in 50 excess of that which may be necessary for the smaller chambers; the volume of air admitted into each compartment of the main tank will, therefore, be under pressure sub- 55 stantially equal to the hydraulic head of the liquid contents.

That the pressure of the air, gas, or vapor 60 may be regulated to obtain the desired re- sults, each air-cell or compartment is sup- plied with the air, gas, or vapor through 65 the medium of a valve-controlled pipe, *n*, the several pipes of the cell in turn connect- ing with an air-supply pipe, *g*, receiving its supply from any suitable source.

The upper sides of the tank are provided 70 with lateral discharge lips or flanges, *p*, over

which the accumulating froth, foam or suds will flow during the froth-forming process, this froth being in turn delivered into an appropriate launder or launders, *q*, extending along one or both sides of the main tank 70 and having an inclined bottom and a discharge, *q'* at one end through which the froth or the broken down concentrated fluid may be delivered for further treatment, or sent to any suitable receiver. 75

As before stated, the tank has an inclined bottom and the porous medium through which the air is delivered into the pulp is likewise inclined and the purpose of this will be understood from the following: 80

The material admitted into the tank through the passage, *g*, is first received into the pocket or chamber, *h*, at the rear end of the tank, just back of the first air-cell, and the material flows over the baffle formed 85 by the high end of the first of the air, gas or vapor cells and over the top surface of the porous medium which overlies the air-cells and gradually fills the several compartments of the tank to the proper level. As 90 the pulp flows down the inclined surface of the porous medium during the filling process, the coarser particles of material too heavy to be raised by the pressure of air, gas, or vapor emitted through the porous 95 medium will naturally gravitate down the incline to the discharge of the bottom of the same and into a well or receiver, *r*, at the discharge end and from which well these coarser particles may be removed in any 100 desired manner. The well or receiver, *r*, forms a collecting chamber for the eventual discharge of the coarse particles, said chamber having, in practice, a suitable plug or cock, or other means for restricting the discharge to approximately correspond to the feed. That this may be better understood 105 it will be observed that the tank is fitted with an overflow pipe, *z*, which is designed to be adjustable and is used for maintaining a 110 definite pulp level within the tank by discharging through this overflow pipe the fines and surplus material which is in excess of the amount discharged from the well or receiver. The coarsest material and sandy 115 portions thereof are discharged through the plug or cock controlling the discharge from the well or receiver and the lighter and slimy material and any excess over and above that which cannot pass through the plug or cock 120 is discharged through the overflow pipe, be- 125 fore mentioned.

Should there be any tendency of the coarse sands or other material to settle upon the porous medium, the velocity of the air, 125 gas, or vapor discharged against this coarse material is sufficient to give a slight move- ment to the particles and this movement, plus the more or less steeply-inclined floor formed by the upper surface of the porous medium, 130

will result in these coarser particles being maintained under movement and gravitating to the discharge end and into the well or settling chamber, before mentioned.

5 As the sands removed from one portion of the porous medium gravitate over the surface they come into contact with the sands which have lodged or tended to lodge upon other lower portions of the material of the 10 porous medium and this gives movement to these latter sands so that in the aggregate these coarser sands are caused to be automatically removed and the surface of the porous medium is kept substantially clean 15 for the discharge of the air, gas, or vapor, and there is no possibility of the sands and fine slimes settling upon and forming a blanket for said porous material.

The tank may be supplied with such other 20 accessories as may be found desirable in the carrying out of the several operations to which such a cell is subjected without departing from the salient features of the present invention.

25 Having thus described my invention what I claim as new and desire to secure by Letters Patent is:—

1. In apparatus of the character described, a tank having a chamber in its bottom to receive a gaseous fluid under pressure, said tank adapted to retain a deep body of mineral-bearing pulp and a frothable agent, and said chamber having a porous upper surface permitting the passage of the gaseous fluid but not liquid or pulp, said surface extending at an incline substantially across the tank in the direction of pulp flow to facilitate the displacement and removal by the aid of gravity of coarse material having a tendency to settle on said surface and blanket the fluid outlets thereof.

2. In apparatus of the character described, a tank adapted to retain a deep body of mineral-bearing pulp, said tank having a 45 sub-divided chamber in its bottom to receive a gaseous fluid under pressure, said chamber having a porous upper surface permitting the passage of the gaseous fluid but not liquid or pulp, and arranged at an incline 50 to facilitate the displacement and removal of coarse material having a tendency to settle on said surface and blanket the fluid outlets thereof.

3. In apparatus of the character described, 55 a tank adapted to retain a deep body of mineral-bearing pulp and a frothable agent, said tank having a bottom declining from the inlet end to the discharge end and said bottom having a chamber into which a gaseous fluid is admitted under pressure, said chamber having a porous upper surface permitting the passage of the gaseous fluid but not the liquid or pulp, said gaseous fluid being delivered into the tank from below in 60 innumerable fine streams.

4. In apparatus of the character described, a compartment tank adapted to receive a mineral-bearing pulp and a frothable agent, said tank having a bottom declining from the inlet to the discharge end, and said bottom having a chamber into which a gaseous fluid is admitted under pressure, said chamber having a porous upper surface permitting the passage of the gaseous fluid but not liquid or pulp, said gaseous fluid being delivered into the compartments of the tank from below in innumerable fine streams, said chamber being sub-divided into cells with a cell underlying each of the compartments of the tank.

5. In apparatus of the character described, a tank having a chamber in its bottom to receive a gaseous fluid under pressure, said tank having an inclined bottom and an inlet at one end and said chamber terminating short of the inlet end of the tank to form a receiving pocket for incoming material, the upper surface of the chamber being of a porous nature adapted to permit the passage of gaseous fluid but not liquid or pulp, and said surface being inclined to facilitate the displacement and removal by the aid of gravity of any coarse material having a tendency to settle on said surface and blanket the fluid outlets thereof.

6. In apparatus of the character described, a tank having a hollow bottom declining from the inlet toward the outlet end of the tank, means for sub-dividing the tank into compartments, means for sub-dividing the hollow bottom into cells corresponding to said compartments, each of said cells having an upper surface composed of a porous medium adapted to permit the passage of gaseous fluid but not liquid or pulp, means for admitting into said cells a gaseous fluid under pressure, said fluid being emitted through the porous medium and into the tank in the form of innumerable fine streams adapted to aerate the contents of the tank 100 and to displace and to assist gravity in removing from the upper surface of the cells the coarse material which has a tendency to settle thereon and blanket the fluid outlets thereof.

7. In apparatus of the character described, a tank having a hollow bottom declining from the inlet toward the outlet end of the tank, means for sub-dividing the tank into compartments, means for sub-dividing the hollow bottom into cells corresponding to said compartments, each of said cells having an upper surface composed of a porous medium adapted to permit the passage of gaseous fluid but not liquid or pulp, means for admitting into said cells a gaseous fluid under pressure, said fluid being emitted through the porous medium and into the tank in the form of innumerable fine streams adapted to aerate the contents of the tank and 120 125 130 135 140 145 150 155 160 165 170 175 180

to displace and to assist gravity in removing from the upper surface of the cell the coarse material which has a tendency to settle thereon and blanket the fluid outlets 5 thereof, said tank having at the discharge end means for receiving the displaced coarse material.

8. In apparatus of the character described, a tank adapted to retain a deep body of 10 mineral-bearing pulp, said tank having a chamber in its bottom to receive a gaseous fluid under pressure, said chamber having a porous upper surface arranged at an incline to facilitate the displacement and removal 15 by the aid of gravity of coarse material having a tendency to settle on said surface and blanket the fluid outlets thereof, said surface adapted to permit the passage of the gaseous fluid but not liquid or pulp, said 20 tank having an inlet at one end and having an overflow at the upper portion.

9. In an apparatus for separating the metalliferous from the non-metalliferous ingredients of an ore mass, the combination 25 of an elongated pulp receptacle, means for feeding thereto an ore pulp containing water and ingredients of both of the said sorts, vertically adjustable means for dividing the said body of pulp into a series of 30 pulp masses the upper parts of which are separated each from the next and the lower parts of which are inter-communicating successively, means for supplying bodies of air at different pressures along the longitudinal 35 lines of the pulp body, means for confining the bubbles generated at one part of the machine longitudinally and causing them to pass to and through the surface of the liquid while separated from the bubbles which 40 pass through another part of the liquid, means for feeding the pulp fluid at one end of the receptacle and means for discharging fluid at planes below the top plane of the pulp fluid.

45 10. The herein described method for separating the metalliferous from the non-metalliferous ingredients of an ore mass, consisting in forming a pulp of said ore ingredients and water, causing the pulp to flow 50 through a receptacle and form therein a pulp body of gradually increasing depth, delivering to the said pulp body at different horizontal planes bodies of air of different pressures, forming therewith bubbles, causing 55 the bubbles to rise for varying distances through the pulp, adhere to and elevate the metalliferous particles, causing the metal-laden bubbles to flow laterally at approximately the top of the pulp, and collecting 60 them and the concentrates thereby carried.

11. The herein described method for separating the metalliferous from the non-metalliferous ingredients of an ore mass, consisting in forming a pulp composed of the 65 said ore ingredients and water, causing the

said pulp to flow through a receptacle and form therein a body of pulp of gradually increasing depth, supplying to the said pulp body at a series of horizontal planes a series of bodies of air increasing gradually in pressure from the pulp feeding end of the body to the discharge end, forming masses of bubbles with the air of each of said bodies, causing the said bubbles to rise through the pulp and adhere to and elevate the metalliferous particles, and causing the metal-laden bubbles to escape from the vertical lines of the pulp body, and collecting the overflowing bubbles and the concentrates carried thereby. 70

12. The herein described method for separating the metalliferous from the non-metalliferous ingredients of an ore mass, consisting in forming a pulp containing the said ore ingredients and water, causing the said pulp to flow through a receptacle and form therein a pulp body of gradually increasing depth, dividing the pulp body into a series of sections longitudinally thereof, supplying bodies of air of relatively low pressure to the shallower sections of the pulp, and other bodies of air of relatively higher pressure to the deeper sections of the pulp body, forming bubbles at the bottom of the pulp body from each of said bodies of air, 90 causing the said bubbles to rise through the pulp and engage with and elevate the metalliferous particles, and causing the bubbles at the top of the pulp to escape from the vertical lines of the said body and collecting 95 the bubbles and the concentrates carried thereby. 100

13. The herein described method for separating the metalliferous from the non-metalliferous ingredients of an ore mass, consisting in forming a pulp containing the said ore ingredients and water, causing the said pulp to flow through a receptacle and form therein a pulp body of gradually increasing thickness, supplying at different horizontal planes bodies of air, varying the pressure of the said bodies of air respectively and independently, causing the air of the said bodies to form bubbles, causing the bubbles of the several sets to travel upward through the 110 mass on paths of varying lengths and to adhere to and elevate the metalliferous particles and collecting the metal-laden bubbles and the concentrates at different points longitudinally of the pulp mass. 115

14. The herein described method for separating the metalliferous from the non-metalliferous ingredients of an ore mass, consisting in forming a pulp composed of the said ore ingredients and water, causing the said pulp to flow through a receptacle and form therein a pulp body of gradually increasing depth, variably dividing the said pulp body longitudinally into each of several masses at the top thereof, the lower parts of the 125 120 130

pulp body being in communication with each other, delivering air in a series of bodies of different pressures to the different parts, feeding pulp to the said body in a 5 continuous stream, and withdrawing water from the said body at a horizontal plane below the top surface plane of the fluid.

15. The herein described method for separating the metalliferous from the non-metalliferous ingredients of an ore mass, consisting in forming pulp thereof with water, causing the said pulp to flow through a chamber having an inclined bottom through which the pulp flows from a place of supply 10 to a place of discharge, dividing the said pulp mass into sections vertically, introducing air under pressure from points outside of the said pulp mass to the bottom thereof at differing horizontal planes corresponding 15 to the aforesaid sections, forming bubbles of relatively large diameter, causing the said bubbles to unite with the metalliferous particles and carrying them to the surface of the pulp mass, and then causing them to 20 flow laterally over the sides at the top thereof and collecting them substantially as set forth.

16. The herein described method for separating the metalliferous from the non-metalliferous ingredients of an ore mass, consisting in forming a pulp comprising the said 30 ingredients and water, causing the said pulp to flow through a receptacle and form therein a pulp body which gradually increases in 35 depth, said pulp body having its top level in a horizontal plane below the plane where the level can be held, supplying to the bottom parts of the said pulp body a series of air bodies of differing pressures gradually 40 increasing along the longitudinal lines of the pulp body, forming bodies of bubbles with the said differing bodies of air, causing the said bubbles to rise through the pulp body for gradually increasing distances 45 to the top of the pulp fluid, forming con-

fined columns of bubbles above the level of the fluid, causing the bubbles of said columns to flow away from the vertical lines of the fluid, and collecting the bubbles of the differing columns and the concentrates 50 carried thereby.

17. In a mechanism for concentrating ores and separating the metalliferous from the non-metalliferous particles, the combination of a relatively elongated and narrow receptacle, means for supplying a pulp fluid thereto, means for permitting the escape of fluid therefrom and variably positioning the normal hydrostatic level thereof at either of several horizontal planes below the top 55 plane of the receptacle, an inclined, bottom wall for the receptacle whereby an interior chamber in the receptacle is provided with a depth gradually increasing from the receiving end to the discharge end, means for 60 forcing air under predetermined pressure through the bottom wall of the receptacle for the forming of bubbles in positions where they are permitted to rise through the pulp. 70

18. In a frothing classifier, a tank and means for admitting air to said tank, said means comprising a series of air chambers arranged at different levels and means for supplying air to the several chambers at different pressures, respectively. 75

19. In a frothing classifier, a tank and means for admitting air to said tank, said means comprising a series of air chambers with tops composed of porous plates, said 80 chambers being arranged at different levels, and means for supplying air to the several chambers at different pressures, respectively.

In testimony whereof I affix my signature in presence of two witnesses.

JOHN M. CALLOW.
